UNITED STATES PATENT OFFICE

2,508,664

WRENCH FOR ROCK DRILL BITS

Gene Joseph Coplen, Denver, Colo.

Application November 5, 1945, Serial No. 626,859

1 Claim. (Cl. 81—55)

1

This invention relates to a rock drill bit wrench. The bits of modern rock drills are threaded onto the extremity of the drill steel shank and, when the bits become dull, it is necessary to remove them from the steel shanks and replace them with a sharpened bit. This procedure has been exceedingly difficult to do due to the fact that the pounding from the pneumatic drill sets the bits so firmly on the steel that it is almost impossible to remove them. The difficulty is increased by the fact that there are no surfaces on the drill bit which can be adequately gripped by a conventional wrench and by the fact that the bits are hardened to such an extent that they cannot be gripped with toothed wrenches, such as pipe wrenches, alligator wrenches and the like.

The principal object of this invention is to provide in a single, simple and highly efficient tool means for firmly holding the drill steel shank in combination with means for gripping and rotating the drill bit thereon so that the bit may be easily and rapidly removed.

Another object of the invention is to construct the improved wrench as a single unit so that there will be no loose, separate pieces or parts which may become lost or displaced.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a plan view of the improved wrench as it would appear when in place on the steel and bit;

Fig. 2 is a side view thereof;

Fig. 3 is a bottom view thereof;

Fig. 4 illustrates the side opposite to that of Fig. 2; and

Fig. 5 is a cross-section, taken on the line 5—5, Fig. 1.

In the drawing a typical drill steel shank is indicated in broken line at 10 with its drill bit at 11. Drill steels have various cross sections such as round, hexagonal, cross, etc. in each case, however, the steel terminates in a rounded shank carrying a concentric, left-hand threaded stud which threads into a similarly threaded socket in the bit 11.

2

The improved wrench employs two similar semi-circular frame members which will be herein designated the upper frame member 12 and the lower frame member 13. The upper frame member 12 is formed with an arcuate dove-tailed socket 14 in its lower surface extending concentrically of the axis of the arc of the frame members. The lower frame member 13 is provided with a corresponding arcuate dove-tailed spline 15 which is slidably mounted in the socket 14 so that the two frame members may be rotated relative to each other about a common axis.

The upper frame member terminates at one extremity in a hinge tongue 16 to which an upper handle 17 is hinged by means of a hinge pin 18, the extremity of the handle being bifurcated to fit over the tongue 16. One extremity of the lower frame member is provided with a similar hinge tongue 19 upon which a lower handle 20 is hinged by means of a second hinge pin 21. The lower handle is similarly bifurcated to fit over its hinge tongue 19. Both hinge pins are secured in place in any desired manner, such as by means of suitable cotter keys 22.

The upper frame member is designed for gripping the drill bit 11 and the lower frame member is designed for gripping the shank of the drill steel 10.

For gripping the bit, the extremity of the handle 17 is provided with a cam 23 positioned eccentrically about the axis of the pin 18. The opposite extremity of the upper frame member 12 terminates in an inwardly extending gripping lug 24. A spacing boss 25 extends inwardly from the upper member intermediate the cam 23 and the lug 24.

It can be readily seen from Fig. 1 of the drawing that the lug 24 fits into one of the concave sides of the bit 11 and, when the handle 17 is rotated in the direction of the arrow "B" in Fig. 1, the cam 23 will forcibly engage the concavity on the opposite side of the drill bit to clamp the latter tightly against the lug 24. The boss 25 engages in the intermediate concave side of the drill bit to assist in centering the latter in the frame member.

For gripping the shank of the drill steel, the handle member 20 is provided with a toothed cam 26 positioned eccentrically of the axis of the hinge pin 21 so that when the handle 20 is swung in the direction of the arrow "A," Fig. 1, the toothed surface of the cam 26 will be forced against the surface of the drill steel 10. The opposite extremity of the lower frame member 13 terminates in a downwardly and inwardly ex-

tending toothed jaw 27 forming an abutment against which the shank 10 is forced by the action of the toothed cam 26. The lower frame member is also provided with a centering boss 28 similar to the boss 25 of the upper frame member.

The hinge pin 13 carries a projecting head 29 which extends into the path of the lower frame member 13 and prevents the two frame members from being turned to a position where the spline 15 will leave its socket 14.

In use, the wrench is opened to the position indicated in broken line in Fig. 1. The drill steel and bit are laid in the open socket formed by the frame members 12 and 13. The handle 20 is then swung to the solid line position of Fig. 1 to bring its toothed cam 26 against the shank 10 and the handle 17 is similarly swung in the direction of the arrow "B" to cause its cam 23 to engage the bit 11. The two handle members are now forced toward each other in the directions of the arrows "A" and "B" causing the upper frame member to slide around the arc of the lower frame member so that the shank 10 and the bit 11 will be rotated in opposite directions about the axis of the bit to loosen the bit from the threads of the shank.

While a specific form of the improvement has been described and illustrated herein, it is desired to be understood that the same may be varied, within the scope of the appended claim, without departing from the spirit of the invention.

Having thus described the invention, what is claimed and desired secured by Letters Patent is:

A wrench for removing grooved drill bits from rock drill steels comprising: two similar, semi-circular frame members lying flat against each other; an arcuate dovetailed groove extending medially of one frame member throughout its

length; a corresponding arcuate dovetailed spline extending medially of the other frame member and being slidably mounted in said arcuate groove so that said two frame members may be rotated about a common axis relative to each other; a first hinge pin positioned at the extremity of the first frame member; a second hinge pin positioned at the opposite extremity of the second frame member; a toothed ratchet cam rotatably mounted on the first hinge pin and adapted to engage said drill steel; an eccentric arcuate cam rotatably mounted on the second hinge pin and adapted to engage in a groove in said drill bit; a gripping lug extending radially inward from said second frame member so as to engage a groove in said bit oppositely to said arcuate cam; a toothed jaw extending outwardly from the side of said first frame member and thence inwardly toward the axis thereof to engage the side of said drill steel oppositely to said tooth ratchet cam; and an operating lever extending from each cam.
